US0D1087046S

(12) **United States Design Patent** (10) Patent No.: **US D1,087,046 S**
(45) Date of Patent: ** Aug. 5, 2025

(54) **TELEVISION RECEIVER**

(71) Applicant: **LG ELECTRONICS INC.**, Seoul (KR)

(72) Inventors: **Jiyeon Lee**, Seoul (KR); **Seungdon Lee**, Seoul (KR)

(73) Assignee: **LG ELECTRONICS INC.**, Seoul (KR)

(**) Term: **15 Years**

(21) Appl. No.: **35/520,707**

(22) Filed: **Mar. 21, 2024**

(80) **Hague Agreement Data**

Int. Filing Date: **Mar. 21, 2024**

Int. Reg. No.: **DM/236644**

Int. Reg. Date: **Mar. 21, 2024**

Int. Reg. Pub. Date: **May 3, 2024**

(30) **Foreign Application Priority Data**

Nov. 8, 2023 (KR) 30-2023-0044082

(51) **LOC (15) Cl.** **14-03**

(52) **U.S. Cl.**

USPC **D14/126**
